UNITED STATES PATENT OFFICE.

FRANCIS H. RICHARDS, OF SPRINGFIELD, MASS., ASSIGNOR OF ONE-HALF
TO THE PRATT & WHITNEY COMPANY, OF HARTFORD, CONN.

MECHANICAL MOVEMENT.

SPECIFICATION forming part of Letters Patent No. 353,760, dated December 7, 1886.

Application filed February 23, 1886. Serial No. 192,967. (No model.)

To all whom it may concern:

Be it known that I, FRANCIS H. RICHARDS, a citizen of the United States, residing at Springfield, in the county of Hampden, State of Massachusetts, have invented certain new and useful Improvements in Mechanical Movements, of which the following is a specification.

This invention relates to that class of mechanical movements in which a series of similar operative parts are successively operated by the same means and in the same way as said parts successively arrive at certain stations in their circuit, the object being to so operate a series of oscillating parts which have an intermittent forward movement in a circular circuit.

To this end the invention consists in the improvements and combinations hereinafter set forth.

20 In the drawings accompanying and forming a part of this specification, Figure 1 is a plan view of a mechanical movement embodying my improvements. Fig. 2 is a front elevation of the same. Fig. 3 is a side elevation, in which some parts are broken away. Fig. 4 is a view similar to the upper portion of Fig. 2, showing certain parts in different positions. Figs. 5, 6, 7, and 8 are views similar to the preceding figures, respectively, showing a modification 30 of the apparatus having an additional improvement.

Similar characters designate like parts in all the figures.

Referring to the first four figures of drawings, the several operative parts are shown supported by a frame-work, which consists in a plain base-plate, 2, and two sides or uprights, 3 and 4. Bearings are formed on said sides for the driving-shaft S, and for a turret-shaft, 40 R, which carries the intermittently-revolving turret T and the oscillating cam C. This cam has imparted thereto a rotary reciprocating or oscillating movement by means of an eccentric, 10, on shaft S, the rod 11 being connected to a 45 stud, 12, fixed in said cam. As shown in the drawings, said movement extends through about ninety degrees; but it may, however, vary in extent; and, furthermore, a suitable cam may be substituted for said eccentric.

The proper forward movement of the turret, 50 which may be in the direction indicated by the arrow in Fig. 3, is produced in a similar manner. A suitable cam, 15, imparts an upward movement to rod 16, which rod, through arm 17, operates pawl 18 to turn the ratchet-wheel 19, which is rigidly fixed to the turret. 55 On completing its upward stroke, the rod, arm, and pawl are returned, as this is permitted by said cam, to their first position, either by weight of rod 16, or by a spring, (not shown,) 60 or by using a return cam, as may be preferred.

The turret carries a series of levers—in this instance four in number, designated by 5, 6, 7 any desired size and form, pivoted at 9 to the respective turret-arms 21, 22, 65 23, and 24. Said levers each have an arm, 20, which works in the cam groove 25 of the cam C, which cam is supposed to be the same or similar to the cam C² shown and described in my application Serial No. 129,850. The nature of said groove is well shown in the drawings, and will be readily understood from a comparison of Figs. 1, 2, and 4. It is so shaped as to hold levers 5, 7, and 8 closed and lever 6 open when the turret and cam stand as shown 75 in these figures. In operating the mechanism this position of the several levers is maintained during the forward movement of the turret, since this and cam C move forward together; next, the cam returns, (the turret standing still, or nearly so,) which will simultaneously close lever 6 and open lever 5, and so on in succession with all the levers comprising 80 the series. Thus each lever is carried to each station successively, and each lever successively is moved by the same cam one way at one station and oppositely at a succeeding station, which, it should be noted, is not necessarily the next succeeding one.

The modified mechanism shown in the last 90 four figures of drawings comprises the same parts as are above described, with the exception that the form of cam C is here made cylindrical, and that the connections between said cam and the levers are here indirect instead of direct. In Fig. 8, also, the turret and cam are shown at the beginning of a forward movement, the lever 5 being swung out ready 95

to be carried around in that position to the station of lever 6 in the other figures. The inner side of each turret-arm is formed to receive a slide, 30, which has a pin, 31, working 5 in groove 25, and rack-teeth 32, meshing with gear-teeth 33, formed on the levers. By means of this construction the said levers may be given a stroke of one hundred and eighty degrees, or more, using a comparatively short 10 cam. It is believed the arrangement has also other advantages—as, for instance, the production of a more rapid movement of the levers with a cam-groove less steep than would otherwise be required.

15 The improved mechanical movement above described constitutes a part of the envelope-machine described in my application Serial No. 129,350, wherein it is shown operating the end-flap-folding wings.

20 Having thus described my invention, I claim—

1. The combination, in a mechanical move-

ment, of the intermittently-revolving turret, the rotary reciprocating cam, grooved substantially as described, a series of arms carried 25 by said turret and operatively connected with the said cam, and mechanism, substantially as described, operating the turret and cam to carry the levers to each station successively and operate them successively at the same station, substantially as set forth. 30

2. The combination, in a mechanical movement, of the intermittently-revolving turret, the cylindrical rotary reciprocating cam, grooved substantially as described, a series of 35 pivoted levers carried in said turret, and a corresponding series of slides, 30, also carried in the turret, said slides being operatively connected to said levers and said cam, substantially as set forth.

FRANCIS H. RICHARDS.
